PLIERS FOR ROUND WORK

Harold L. McAfee, Bartlesville, Okla.

Application November 12, 1946, Serial No. 709,380

3 Claims. (Cl. 81—44)

1

This invention relates to mechanics' tools, and more especially to pliers having substantially parallel non-crossed pivoted handles with crossed jaws; an object of the same is to produce a tool for use by mechanics where an elevating and turning action is desired, and where the turning action causes a multiplying of the gripping power applied to said handles.

This invention consists in the novel construction of the plier-handles and integral jaws hereinafter described.

These and other objects and advantages of this invention will be fully set forth in the following description, made in connection with the accompanying drawing in which like reference characters refer to similar parts through the views and in which:

Figure I is a view in side elevation of the improved mechanic's tool, embodying the invention.

Figure II is a view in front elevation of the tool embodying this invention.

Referring to the drawing, a tool construction is shown comprising a handle or member 11. While this member could be variously formed, in the embodiment of the invention illustrated it is in the form of a solid handle and is slightly curved to meet the desires of a mechanic's hand and can be referred to as the stationary handle. Member 12 constitutes the second handle which is grasped by the mechanic's fingers and is shown solid and has one straight side and suitably curved inner portions. Member 11 has a terminal or stationary jaw end 15. Member 12 which moves with the movement of the mechanic's fingers has a terminal jaw end 14 which moves as said handle 12 moves, and it has a recess or cut away portion 16 adjacent the jaw end 14. The recess 16 is of sufficient length to permit free play between the long curved jaw 15 and said portion 16 which moves as handle 12 is moved. Members 11 and 12 have intermediate sections 17 and 18 respectively which are pivotally connected together by pintle 13.

The jaw 14 is a short jaw formed at an angle with the straight side of handle 12 and has lateral teeth 19 on its rough outside operating surface, and said surface is substantially of non-circular contour. The jaw 15 has a flat portion 29 adjacent its free end and a smooth curved operating surface 21, as shown, forming a concave throat portion, or face, in conjunction with the opposite jaw 14. The operating surfaces 19 and 20 tend to form a recess 22 of substantially circular form on the one side of the smooth jaw thereof when the jaws 14 and 15 are closed. A circular object, such as a rod is shown dotted by

2

numeral 23 and as pressure is applied by jaws 14 and 15 to said object 23, said object 23 has a tendency to roll into the jaws of the tool in a direction toward the pivot 13 as shown dotted by 23' and 23''.

With the described construction it will be seen that when the curved handle member 11 is held stationary and member 12 is moved toward or from handle member 11 about pivot 13, that jaw member 14 will be caused to move towards jaw member 15 due to the fact that the jaws are crossed even though the handles are not crossed. By having the jaws crossed and having the one jaw 15 longer than the opposite jaw 14, and with jaw 15 having a smooth circular form while jaw 14 is of short non-circular form and has lateral teeth on its operating surface, an elevating or turning action is accomplished as described above, as any object gripped between the jaws has a tendency to roll into the throat of the two jaws in a direction toward the pivot 13, this action cannot be accomplished by the ordinary type mechanic's tool. Since jaw 14 has lateral teeth on its gripping surface and the jaw 15 has a smooth circular surface, when pressure is applied to an object by said jaws, the object cannot slip upon the lateral teeth of jaw 14 but it can slip against the smooth surface of jaw 15. As the pressure between the jaws is increased, the clamped object slips and turns until it reaches the base of the throat formed by said jaws. The object grasped is always forced further into the throat of the two jaws of the pliers or the mechanic's tool in a direction of pivot 13 until the object cannot be moved further and at this point the action causes a multiplying of the gripping power applied to said handles and the object is tightly held and prevented from slipping within the jaws.

Much difficulty has been experienced in obtaining a mechanic's tool that will remove a hard set circular nut, or hexagon nut or screw, where space is limited. Often the space is so limited that only the ordinary type pliers or tool can be inserted to grasp the circular nut and no movement of the pliers can be given once the object is grasped. With the ordinary pliers with crossed jaws the object is forced out of the jaws when only pressure is applied. With this novel tool as shown and described, once the object is grasped, the object will be held within the jaws until released by the operator and if a nut is hard set, often the application of pressure alone on said nut will cause it to become loosened from the hard set by the turning action taking place within the

jaws, said action only being an initial action as the object is finally grasped tightly and prevented from slipping within the jaws by the lateral teeth 19 formed on the operating surface of jaw 14 which moves as handle 12 is moved by the mechanic's fingers.

From the above description it will be seen that a very simple and very efficient construction of a tool has been provided in which the one jaw with teeth moves toward the other jaw without teeth which give a turning action in a direction of the pivot as well as a rigid tight grip. The movement of the jaws is very accurate, a turning action is provided when pressure is applied on certain objects between the jaws, the turning action continues until the object is moved inward into locking engagement with the jaws; after which any tendency for a twisting movement which might occur is prevented by the rough surface on the shorter jaw with teeth and locked by the longer jaw without teeth and of circular contour. This type tool is easily operated, works with precision, and can be made in small or larger sizes. A novel, neat and efficient tool has been provided.

It will of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What I claim is:

1. In pliers, the combination of a pair of handles, one of said handles being curved to fit the operator's hand and considered the stationary handle, the other handle being substantially straight and considered the movable handle, each of said handles having an intermediate section, said sections pivotally connected together by a pintle, a jaw formed integral with each of said handles, said jaws crossing each other and having adjacent operating surfaces, the jaw on the movable handle forming a short outer jaw with lateral teeth on its operating surface, the jaw on the stationary handle being off-set and longer than the jaw on the movable handle and forming a rear jaw, said rear jaw having a smooth operating surface thereon which is curved to form a concave portion with respect to said outer jaw, the two jaws forming a closed throat portion in conjunction with each other, said throat extending longitudinally and rearwardly thereof, whereby the object to be moved is grasped between the opposite faces of said jaws and upon movement of the handle connected with the outer jaw having teeth thereon an elevating or turning action is effected upon said object, turning the object in a rearwardly direction into the closed end of the throat formed by the jaws, said action being due to the lateral teeth on the outer jaw solely preventing slipping of the object thereon while the smooth surface upon the rear jaw permits slipping of the object thereon when pressure is applied to the handle connected with the outer jaw having teeth thereon.

2. In pliers, the combination of a pair of handles, one of which is substantially straight and considered the lower and movable handle, the other handle being curved to fit the operator's hand and considered the upper and stationary handle, each of said handles having an inter-

mediate section, said sections pivotally connected together by a pintle, a jaw formed integral with each of said handles, said jaws crossing each other and having adjacent operating surfaces, the jaw on the lower and movable handle forming a short downwardly turned straight jaw, the jaw on the upper and stationary handle being off-set and longer than the jaw on the movable handle and forming a curved rear jaw, the terminal ends of the jaws being disposed on one side of a horizontal plane including the lower handle and on the side of said plane farthest from a horizontal plane including the curved handle, the two jaws forming a closed throat portion in conjunction with each other where they cross, said throat extending longitudinally and rearwardly thereof, whereby the object to be moved is grasped between the opposite faces of said jaws and upon closure of said handles a turning action is effected by the jaws forcing the object in a rearwardly direction into the closed end of the throat formed by the jaws.

3. In a turning tool, the combination of a pintle and a pair of members, each member respectively comprising a straight intermediate portion, a rearwardly extending handle at the rear end of the intermediate portion, and an arm at the forward end of the intermediate portion terminating in an angularly disposed jaw; one of said handles being curved and considered the stationary handle and the other handle substantially straight and considered the movable handle, the jaw formed on the straight handle being rather short, the jaw formed on the curved handle being longer than the jaw on said straight handle and of curved formation, said pintle pivotally connecting the intermediate portions of the members together at a point between the members, said short jaw having teeth on its inner operating surface, the longer jaw having a smooth operating surface and curved to form a concave throat portion in conjunction with the shorter jaw at the closed end thereof adjacent where they cross, said throat extends longitudinally and rearwardly thereof, whereby the object to be moved is grasped between the opposite faces of said jaws and upon closure of said handles an elevating or turning action is effected by the jaws, the teeth on the short jaw preventing slipping of the object upon its operating surface while the smooth jaw permits slipping of the object upon its smooth operating surface in a direction of the pivot.
